DESIGN FOR AN INDIRECT ELECTRIC FLOOR LAMP

Bert A. Dickerson, Decatur, Ill., assignor to Faries Manufacturing Company, Decatur, Ill.

Application February 17, 1937, Serial No. 67,708

Term of patent 3½ years

To all whom it may concern:

Be it known that I, Bert A. Dickerson, a citizen of the United States and a resident of Decatur, in the county of Macon and State of Illinois, have invented a new, original, and ornamental Design for an Indirect Electric Floor Lamp, of which the following is a specification, reference being had to the accompanying drawing, forming a part thereof.

The figure is an elevational view of an indirect electric floor lamp, showing my new design.

I claim:

The ornamental design for an indirect electric floor lamp, substantially as shown.

BERT A. DICKERSON.
